UNITED STATES PATENT OFFICE.

GEORGE HOFFMAN, OF BUFFALO, NEW YORK.

AUTOMATIC DRAINER FOR CELLARS, &c.

973,851.

Specification of Letters Patent. Patented Oct. 18, 1910.

Original application filed September 27, 1909, Serial No. 519,756. Divided and this application filed June 18, 1910. Serial No. 567,603.

To all whom it may concern:

Be it known that I, GEORGE HOFFMAN, a citizen of the United States, residing at Buffalo, in the county of Erie and State of New York, have invented new and useful Improvements in Automatic Drainers for Cellars, &c., of which the following is a specification.

This invention relates to an automatic drainer which is more particularly designed for removing accumulated water in a cellar, although the same may also be used for other like purposes.

The object of this invention is the production of an improved drainer of this character which is not liable to become clogged or rendered inoperative.

This application is a subdivision of an application for patent filed by myself September 27, 1909, Serial No. 519,756.

In the accompanying drawings: Figure 1 is a sectional view showing my improved automatic drainer installed in the well of the cellar or other place to be drained. Fig. 2 is a vertical longitudinal section of the drainer, on an enlarged scale. Fig. 3 is a horizontal section, on an enlarged scale, in line 3—3, Fig. 2.

Similar letters of reference indicate corresponding parts throughout the several views.

A represents the well, pit or depression which is formed in a cellar or other place and in which the water to be drained accumulates. Within this well is arranged my improved drainer for removing the water therefrom. In its general organization this drainer comprises an upright pressure conduit or pipe B through which descends the water lifting medium, such as steam or water under pressure, means for controlling the pressure medium arranged in the pressure pipe, an upright discharge pipe or conduit C operatively connected at its lower end with the lower end of the pressure conduit by a return bend c, and an ejector arranged in said discharge pipe for removing the water from said well. The pressure pipe or conduit comprises upper, intermediate and lower pipes or sections d, d¹, d², respectively. Between the upper and intermediate sections is arranged the straining or screening device E for catching any foreign matter, such as small fishes or sticks contained in the pressure water and preventing

the same from reaching the valve mechanism and the water ejecting mechanism.

Between the intermediate and lower pressure pipe sections d¹, d² is arranged the automatic valve mechanism which controls the supply of water to the ejector and which is preferably constructed as follows:

H represents a valve casing having an upper inlet h which is connected with the lower end of the intermediate pipe section d¹, a lower outlet h¹ which is connected with the upper end of the lower pipe section d², a partition I arranged between the inlet and outlet of the casing and provided with a port or passage i, and a tubular neck J projecting forwardly from the front side of the casing in line with said port.

L represents the stopper of the valve which is mounted on a horizontal valve stem M provided on the outside of said casing with inner and outer shoulders o, o¹.

The opening and closing of the stopper is effected by means of a float R which is adapted to be raised and lowered by the variation of the level of water in the well. This float is operatively connected with the valve stem by means of an upright shifting rock lever pivotally supported on the valve casing and having its lower arm s constructed in the form of a fork which straddles the valve stem between its inner and outer shoulders o, o¹, while its upper arm s¹ has secured thereto the inner end of an extension-rod S which latter carries the float at its outer end.

When the level of the water in the well is below normal, the float drops into its lowermost position, as shown in Fig. 1, whereby the rock lever is turned so that its lower arm engages the inner shoulder of the valve stem and the latter is moved inwardly so that the stopper engages its seat and closes the valve thereby shutting off the supply of water or other pressure medium.

When the water rises above the normal in the well, the float turns the rock lever so that its lower arm engages the outer shoulders of the valve stem, the latter will be moved outwardly and the stopper will be opened, thereby permitting water under pressure to pass through the valve to the ejecting device. The ejecting device which operates by the action of the pressure me-

dium for discharging the water from said well is constructed as follows:—

V represents a cylindrical enlargement or chamber arranged on the lower part of the discharge pipe C and provided with a plurality of openings v in its wall, thereby forming a screen or strainer which permits the water in the well to enter said chamber but excludes any large particles.

10 W represents the tubular body of a lining or bushing arranged within the discharge pipe above the straining chamber V and provided at its lower end with an enlargement or head w which is arranged in 15 said straining chamber and forms an upwardly facing shoulder w¹ which bears against the top of said straining chamber. This bushing is preferably held in place by a set screw x engaging with the same and 20 arranged in the discharge pipe.

Y represents an upwardly tapering ejector nozzle which is arranged centrally in the straining chamber and provided with an external annular flange y which is secured 25 by a screw joint to the lower end of said straining chamber. The upper end of the ejector nozzle projects into the downwardly flaring lower part z of the bore of the bushing and its lower end is secured by a screw 30 joint with the adjacent upwardly turned end of the return bend c.

When the controlling valve is opened, the pressure water or other pressure medium passes upwardly through the ejector nozzle 35 into the bushing in the form of a jet, thereby creating a suction whereby the water is drawn from the well through the perforated straining chamber and ejected upwardly through the bushing and from the upper 40 end of the discharge pipe to a sewer or other place.

The body and head of the bushing are constructed of wood so as to prevent scale, lime or dirt from solidifying therein and 45 clogging the same. If any material accumulates in the ejector bushing and inter-

feres with its operation, the same can be easily removed from the discharge pipe, cleaned and replaced without liability of injuring the same, inasmuch as the solid 50 impurities do not cling tenaciously to the bushing on account of its being made of wood, thereby permitting the draining device to be always maintained in the highest state of efficiency.

It has been found by experience that if the water removed from a well in a cellar by the ejecting device is conducted through a metal suction or outlet pipe, as is usually the case, the cement or lime in the water adheres to the bore of this pipe and clogs the same. To prevent this, it has been proposed to line the outlet suction pipe C with glass which overcomes the tendency to clog but is objectionable on account of its liability 65 to break. A lining of wood for the outlet or suction pipe, as proposed in the present case, not only prevents clogging but also is not liable to break by ordinary use.

I claim as my invention:

A draining device comprising an upright discharge pipe, an enlarged straining chamber connected with the lower end of said discharge pipe and provided in its walls with perforations, a tubular bushing of 75 wood having a comparatively narrow upper part arranged in said discharge pipe and an enlarged lower part arranged in said chamber and having the lower part of its passage flared downwardly, and an 80 ejector nozzle arranged centrally in said chamber below the lower end of said bushing and having an external annular flange which is connected by a screw joint with the lower end of said chamber.

Witness my hand this 17th day of June, 85
1910.

GEORGE HOFFMAN.
